COMBINATION FIXTURE

Alfred Camp, Brea, Calif., assignor to Repcal Brass Mfg. Co., Los Angeles, Calif., a corporation of California

Application November 2, 1953, Serial No. 389,560

1 Claim. (Cl. 230—92)

2

head, an ejector is provided in the cross. Such backing up might be caused by partial obstruction of the spout 24 or pipe 26.

The ejector is formed by providing a wall 34 at the 5 extremity of arm 23 and a similar wall 36 at the extremity of arm 28. The two walls are spanned by a solid member or bridge 38 which in this embodiment is half the thickness of the cross 14. A port 40 communicates arm 23 with arm 28.

10 The wall 36 has a bore 42 therein which communicates with the interior of the horizontal arm 44 of cross 14.

Thus when the spout is open permitting flow there-through, water entering arm 44 of cross 14 flows through port 42 into pipe 26. Since port 42 is of smaller cross 15 section than the effective cross section of arm 44, its velocity is increased creating a venturi effect and sucks air through the shower head 20 and port 40 preventing water backing up and dripping from the shower head. When the diverter valve 30 is moved to the spout closing 20 position water backs up through port 40 and pipe 22 and is sprayed from the shower head.

While what hereinbefore has been described is the preferred embodiment of this invention it is readily apparent that alterations and modifications can be resorted 25 to without departing from the scope of this invention and such alterations and modifications are intended to be included within the scope of the appended claim.

I claim:

30 A combination fixture comprising: a cross having a pair of inlets and a pair of outlets, walls between said inlets and said outlets, a bridge spanning said walls and having an unobstructed port therein communicating said outlets independent of said inlets, and an unobstructed opening through one of said walls permitting flow through 35 one of said outlets, flow through said last mentioned outlet drawing air through said port from the other outlet preventing water accumulation or discharge from said last mentioned outlet.

40
